UNITED STATES PATENT OFFICE.

STACY B. HASELTINE, OF CHICAGO, ILLINOIS, ASSIGNOR, BY MESNE ASSIGNMENTS,
TO W. H. MINER, INC., A CORPORATION OF DELAWARE.

FRICTION SHOCK-ABSORBING MECHANISM.

Application filed September 12, 1924, Serial No. 737,351. Renewed December 20, 1928.

This invention relates to improvements in friction shock absorbing mechanisms.

One object of the invention is to provide a friction shock absorbing mechanism, more

5 particularly adapted for railway draft riggings, wherein is obtained high capacity due to large frictional areas, together with quick and easy release.

Another object of the invention is to provide 10 a friction shock absorbing mechanism of the intercalated plate type, including spreading means and a plurality of sets of opposed friction elements coacting with the spreading means, together with means for forcing the 15 opposed elements of each set laterally toward each other as the sets are spaced apart, thereby placing the friction plates under lateral pressure.

Still another object of the invention is to 20 provide a mechanism of the character indicated wherein a preliminary action of the follower means during compression prior to engagement and movement of the plates by the follower means is obtained and then a relative movement of the friction plates after 25 the full wedging action has been set up.

Other objects and advantages will more clearly and fully appear from the description and claims hereinafter following.

30 In the drawings forming a part of this specification, Figure 1 is a horizontal, longitudinal, sectional view of a portion of a railway draft rigging, showing my improvements in connection therewith. Figure 2 is a front 35 end elevational view of the shock absorbing mechanism proper. Figure 3 is a transverse, vertical, sectional view of the shock absorbing mechanism proper, corresponding substantially to the line 3—3 of Figure 1. Figure 40 4 is a detail, perspective view, broken away, of the front end portion of one of the friction elements used in connection with my improved mechanism. And Figure 5 is a view similar to Figure 3, illustrating a different embodiment of the invention.

45 In said drawings, referring first to the embodiment of the invention illustrated in Figures 1 to 4, inclusive, 10—10 indicate channel-shaped center or draft sills of a railway car underframe, to the inner faces of which are secured front stop lugs 11—11 and rear stop lugs 12—12. A portion of the drawbar is shown at 13, to which is operatively connected a yoke 14 of well known form. The shock 50 absorbing mechanism proper, including the

front follower 15, is disposed within the yoke 14, and the movable parts of the draft rigging are supported by a detachable saddle plate 16.

The improved shock absorbing mechanism 60 proper, as shown in Figures 1 to 4 inclusive, comprises, broadly: a follower-acting friction shell A; four friction elements B—B; two groups of friction plates C—C; a wedge block D; a pair of friction shoes E—E; a spring 65 resistance F; a spring follower G; and a retainer bolt H.

The friction casing A is of substantially octagonal form, having spaced, horizontally disposed top and bottom walls 17—17, spaced, 70 vertically disposed side walls 18—18, inclined connecting walls 19—19 and a transverse end wall 20, as clearly shown in Figures 2 and 3, the end wall 20 extends beyond the inclined walls 19 and coacts with the rear stop lugs 12 75 in the manner of a follower. The inclined walls 19 present longitudinally disposed, interior, opposed friction surfaces 21 arranged in pairs at opposite sides of the mechanism, the surfaces 21 of each pair diverging laterally 80 toward the center of the mechanism. On the inner side, the wall 20 is provided with a hollow projection 22 extending from the top to the bottom wall of the casing and spaced equally from the opposite sides of the same. 85 At the inner end the projection 22 is provided at the opposite sides thereof with forwardly converging wedge faces 23—23, the portion 22 forming in effect a wedge member integral with the casing A.

90 The friction elements B are four in number and are arranged in pairs at opposite sides of the mechanism, as clearly shown in Figures 1, 2, and 3. As shown in Figs. 1 to 4 inclusive, the elements B are of like construction, each being in the form of an elongated bar of generally triangular cross-section having a longitudinally disposed, outer flat friction surface 121 correspondingly laterally inclined to and adapted to cooperate with one 100 of the faces 21 of the shell A. On the inner side, that is, the side nearest the axis of the mechanism, each element B presents a longitudinally extending, vertical friction surface 133, adapted to cooperate with one of the friction shoes E. At the forward end each element B is provided with an enlargement 24 laterally projecting therefrom (see Fig. 4). The enlargement 24 has an outer wedge face 25 adapted to cooperate with the wedge D. 110

The wedge faces 25 of the elements B at the opposite sides of the mechanism converge inwardly as clearly shown in Figure 1. The inner ends of the enlargements 24 of the elements B present transverse abutment faces 26 adapted to bear on the front face of the spring follower G. As clearly shown in Figure 1, the front ends of the elements B are normally slightly spaced from the inner surface of the follower 15 and the rear ends thereof are spaced a sufficient distance from the inner surface of the transverse end wall of the shell A to permit the full compression stroke of the mechanism by the time the elements B come into actual engagement with said end wall of the shell.

The friction plates C comprise two groups arranged at opposite sides of the mechanism, each group preferably consisting of three plates, two outer similar plates 27-27 and an intermediate plate 28. The plates 28 are provided with lateral extensions 29 at their front ends serving as lugs which are adapted to cooperate with the outer face of the spring follower G to effect restoration of these parts to normal position. The plates are cut away on their inner faces adjacent the outer ends thereof as indicated at 30 to provide proper clearance between the same and the wedge block D. The plates 27 of each group are provided with a lateral extension 31 at the rear end thereof providing a lug adapted to cooperate with the corresponding friction wedge shoe E to effect restoration of the plates to normal position. As clearly shown in Figures 2 and 3, the three plates 27, 27 and 28, comprising each group, are interposed between the corresponding friction elements B at the same side of the mechanism, and are adapted to be placed under lateral pressure by the latter when the same are forced to approach each other.

The wedge block D is provided with a transverse outer face 32 adapted to abut the front follower 15 and a pair of inwardly converging wedge faces 125 at the opposite sides thereof correspondingly inclined to and adapted to cooperate with the wedge faces 25 of the two sets of friction elements B.

The friction wedge shoes E are two in number, and are disposed at the rear end of the mechanism, being interposed between the sets of friction elements at the opposite sides of the mechanism and the wedge member 22. The two shoes E are of like construction, each having a flat outer side face 33 adapted to cooperate with the friction surface 133 of the two members B at the same side of the mechanism. Each shoe E is also provided on the side nearest the axis of the mechanism with a wedge face 123 correspondingly inclined to and adapted to cooperate with one of the wedge faces 23 of the wedge 22.

The spring resistance element F is interposed between the spring follower G and the

friction wedge shoes E, the same comprising an inner relatively light coil and an outer relatively heavy coil. In order to hold the springs properly centered the shell A is provided with interior, longitudinally disposed top and bottom ribs 34. The parts of the mechanism are held in assembled relation under initial compression by the retainer bolt H which has its opposite ends anchored respectively to the rear wedge member 22 and the front wedge block D, the shank of the bolt extending through the inner coil of the spring resistance and aligned openings provided in the spring follower G, and wedges D and 22.

It will be evident that the relative position of the plates C and the springs F is such that lateral shifting of any of these parts is practically prevented, except to a very limited extent.

In the normal position of the parts, the front ends of the plates 28 are normally slightly spaced from the front follower 15 and the rear ends of the plates 27 are spaced from the inner surface of the wall 20 in the casing A a distance substantially equal to the spacing of the plates 28 from the front follower. As clearly shown in Figure 1, the front ends of the plates 27 and the rear ends of the plates 28 are spaced a sufficient distance from the front follower and the transverse wall 20 of the casing A respectively to permit the full compression stroke of the mechanism. The parts are so proportioned that when the front follower comes into abutment with the outer end of the casing A, the three plates of each group will also be brought into abutment with the end wall of the casing, the plates together with the casing acting as a substantially solid stop-column adapted to transmit the actuating pressure directly to the stop lugs of the draft sills.

The operation of the improved shock absorbing mechanism illustrated in Figures 1 to 4, inclusive, is as follows, assuming a compression stroke of the mechanism and an inward movement of the drawbar. Upon inward movement of the drawbar the front follower 15 will be carried inwardly, forcing the wedge block D rearwardly also, setting up a lateral wedging or spreading action between the latter and the friction elements B at the opposite sides of the mechanism. This lateral spreading action of the opposed friction elements at the top and bottom of the mechanism causes these elements to be wedged toward the horizontal center plane of the mechanism through the action of the inclined faces 21 of the shell, thereby placing the friction plates C under pressure. The actuating force will be transmitted to the shoes E at the rear end of the mechanism through the medium of the spring F, thereby setting up a wedging action between the shoes and the wedge 22, to force the shoes into frictional engagement with the rear ends of the mem-

bers B, at the same time laterally spreading the rear ends of the elements B in a manner similar to the spreading action at the front end of the mechanism. During the continued inward movement of the front follower, the elements B will be forced inwardly of the shell by the wedge member D, sliding longitudinally on the friction surfaces 21 of the shell and on the friction surfaces 33 of the shoes E. It will be evident that the spring follower G will be carried rearwardly with the elements B by engagement with the shoulders 26 thereof, causing the follower to move away from the lugs 29 of the friction plates 28. The inward movement of the parts as hereinbefore described, will continue until the front ends of the plates 28 are engaged by the follower 15, whereupon these plates will be picked up and moved longitudinally relatively to the plates 17. It will be evident that during the preliminary action of the mechanism hereinbefore described, the two groups of plates will be carried rearwardly with the elements B due to the frictional engagement therebetween, until the rear ends of the plates 27 come into abutment with the end wall 20 of the casing, whereupon the two groups of plates will remain substantially stationary while the members B slip thereon. The plates are thus held stationary until relative movement of the plates 27 and 28 is effected by the front follower engaging the front ends of the plates 28 as hereinbefore pointed out. During the bodily inward movement of the groups of plates and the elements B, the lugs 31 of the plates 27 will be moved out of engagement with the rear ends of the shoes E. The compression stroke continues in the manner hereinbefore described, either until the actuating force is reduced or until the front follower 15 engages the front end of the friction shell A whereupon the actuating force will be transmitted directly through the shell and the friction plates as hereinbefore described, these elements acting in the manner of a solid column.

When the actuating pressure is relieved, the wedge pressure is instantly reduced, due to the wedge member dropping away from the friction shoes and friction elements, permitting the spring to expand and force the elements B and shoes E outwardly. After the wedging pressure on the plates has been reduced, further outward movement of the spring follower G away from the shoes E will effect restoration of the friction plates to normal position, the plates 28 being forced forwardly by engagement with the spring follower and the plates 27 being carried forward by frictional contact with the plates 28 until the lugs 31 of the plates 27 come into engagement with the rear ends of the shoes E, whereupon movement of the plates 27 will be arrested. It will be evident that the restoring action of the plates is not effected until the

wedging pressure has been effectively reduced, as the wedge member and the elements B are forced outwardly prior to any engagement of the spring follower G with the plates, due to the spacing of the follower from the lugs 29 of the plates 28 during the compression stroke of the mechanism. During draft, the action is substantially the same as that described with the exception that the friction shell A is moved forwardly toward the follower 15 when the latter is held stationary by engagement with the front stop lugs. As wear occurs on the various friction and wedge surfaces, compensation therefor will be had by the expansion of the spring resistance F, which as hereinbefore described is under initial compression, the latter gradually forcing the friction shoes E and elements B apart longitudinally sufficient clearance being provided to permit of this action.

Referring next to the construction illustrated in Figure 5, the improved shock absorbing mechanism, as shown, is substantially the same as that shown in Figures 1 to 4 inclusive, with the exception that the friction plates are of wedge shape in cross section, having their coacting faces radially disposed and that the coacting faces of the friction elements are correspondingly disposed and that the friction shell is provided with additional interior friction surfaces with which the outer edges of the friction plates cooperate. As shown in Figure 5, a friction shell of substantially octagonal form similar to the shell A is provided, the same being indicated by A'. Four friction elements B' are provided, each of which is, in all respects, similar to the friction elements B hereinbefore described. Interposed between the friction elements B' of each set, are three friction plates 127-127, and 128 each being of wedge shape in cross section and having their coacting faces radially disposed with reference to the longitudinal axis of the mechanism. The outer edges of the plates 127 and 128 cooperate with the inner surfaces of the side walls 118 of the casing, the inner surfaces of said side walls 18 being curved as shown and presenting interior friction surfaces 134 adapted to cooperate with similarly curved faces on the outer edges of the friction plates 127 and 128.

The operation of the mechanism illustrated in Figure 5 is substantially the same as that hereinbefore described, with the exception that, due to the radial arrangement of the coacting faces of the friction plates C' and the friction elements B', the friction plates are additionally wedged laterally outwardly, and pressed against the friction surfaces 134 of the shell, thereby providing additional friction during the compression stroke of the mechanism.

I have herein shown and described what I now consider the preferred manner of car-

rying out my invention, but the same is merely illustrative, and I contemplate all changes and modifications that come within the scope of the claims appended hereto.

5 I claim:

1. In a friction shock absorbing mechanism, the combination with a friction shell having interior wedge surfaces converging outwardly laterally of the mechanism; of a plurality 10 of friction wedge elements cooperating with said shell surfaces; spreading means co-operating with said elements for forcing the same outwardly of said wedge surfaces; a main spring resistance opposing movement 15 of said friction elements; and intercalated, relatively movable, longitudinally disposed friction plates interposed between said elements.

2. In a friction shock absorbing mechanism, 20 the combination with a plurality of friction elements; of laterally acting spreading means for said elements for forcing said elements laterally outwardly; a friction member having faces inclined to the direction of 25 the effective-outward spreading forces of said means and co-operating with said elements to displace the same toward each other; a plurality of intercalated, relatively movable friction plates interposed between said elements, follower means for effecting movement 30 of said plates and a main spring resistance opposing movement of said elements.

3. In a friction shock absorbing mechanism, 35 the combination with a friction shell having interior wedge faces converging laterally of the mechanism; of a plurality of longitudinally disposed friction elements each having a wedge face correspondingly inclined to and co-operating with one of said 40 shell faces; spreading means for forcing said elements transversely of said shell wedge faces; a main spring resistance opposing movement of said friction elements; and intercalated, relatively movable, longitudinally 45 disposed, friction plates interposed between said elements.

4. In a friction shock absorbing mechanism, 50 the combination with a plurality of longitudinally disposed, elongated friction elements; of laterally acting spreading means for said elements; a friction member having opposed converging faces inclined to the direction of the effective spreading forces of 55 said means and co-operating with said elements to displace the same laterally toward each other; a plurality of longitudinally disposed, intercalated, relatively movable friction plates interposed between said elements; and spring resistance means opposing movement 60 of said friction elements.

5. In a friction shock absorbing mechanism, 65 the combination with a friction shell having opposed sets of longitudinally disposed, friction surfaces laterally diverging toward the axis of the mechanism; of op-

posed, longitudinally disposed friction elements co-operating with said shell friction surfaces; wedge means co-operating with said elements; a main spring resistance; and a plurality of relatively movable, longitudinally disposed, intercalated friction plates 70 between the opposed elements.

6. In a friction shock absorbing mechanism, 75 the combination with a friction shell having a plurality of opposed sets of friction surfaces laterally diverging toward the axis of the mechanism; of a plurality of sets of opposed, longitudinally arranged friction elements co-operating with the shell friction surfaces; a group of relatively movable, 80 intercalated friction plates interposed between the elements of each set of elements; wedging means disposed between said sets of elements and co-operating therewith; and a main spring resistance. 85

7. In a friction shock absorbing mechanism, 90 the combination with a friction shell having two opposed sets of friction surfaces laterally diverging toward the axis of the mechanism; of a main spring resistance; wedge spreading means; two sets of friction elements co-operating with said wedge spreading means, said sets being disposed on opposite sides of said means, each element co-operating with one of said shell friction surfaces; and a plurality of longitudinally disposed, intercalated friction plates, said plates being divided into two groups disposed on opposite sides of the mechanism and each group being interposed between the elements 95 of one of said sets.

8. In a friction shock absorbing mechanism, 100 the combination with a friction shell having interior wedge surfaces converging laterally of the mechanism; of a plurality of friction wedge elements having wedge faces correspondingly inclined to and co-operating with said shell surfaces; laterally acting spreading means cooperating with said elements for forcing the same outwardly, a 105 main spring resistance opposing movement of said wedge elements; intercalated, relatively movable, longitudinally disposed friction plates interposed between said elements; and means for restoring said elements and plates 110 to normal position.

9. In a friction shock absorbing mechanism, 115 the combination with a plurality of elongated friction elements having longitudinally disposed friction surfaces; a plurality of friction shoes co-operating with said friction surfaces; wedge spreading means for said shoes and elements; a friction member having faces inclined to the direction of the effective spreading force of said means 120 and co-operating with said elements to displace the same laterally toward each other; a plurality of relatively movable, intercalated, friction plates interposed between said elements; and a main spring resistance. 125

10. In a friction shock absorbing mechanism, the combination with a plurality of elongated friction elements having longitudinally disposed friction surfaces, each element 5 having a wedge face on one end thereof; of a plurality of friction shoes co-operating with said friction surfaces; wedge spreading means for said shoes and elements, said means including wedge members co-operating respectively with said shoes and the wedge faces 10 of said elements; a friction member having faces inclined to the direction of the effective spreading force of said means and co-operating with said elements to displace the same laterally toward each other; a plurality of 15 relatively movable, intercalated friction plates interposed between said elements; and a main spring resistance. 100
11. In a friction shock absorbing mechanism, the combination with a plurality of elongated friction elements having longitudinally disposed friction surfaces, each element having a wedge face on one end thereof; of a plurality of friction shoes co-operating with 20 said friction surfaces; wedge spreading means for said shoes and elements, said means including wedge members co-operating respectively with said shoes and the wedge faces 25 of said elements; a friction member having faces inclined to the direction of the effective spreading force of said means and co-operating with said elements to displace the same laterally toward each other; a plurality of 30 relatively movable, intercalated friction plates interposed between said elements; a main spring resistance; and means for restoring said plates and elements to normal position, said last named means including abutment members on certain of said plates co- 35 operating with said shoes. 105
12. In a friction shock absorbing mechanism, the combination with a plurality of elongated friction elements having longitudinally disposed friction surfaces, each element 40 having a wedge face on one end thereof; of a plurality of friction shoes co-operating with said friction surfaces; wedge spreading means for said shoes and elements, said means including wedge members co-operating respectively with said shoes and the wedge faces 45 of said elements; a friction member having faces inclined to the direction of the effective spreading force of said means and co-operating with said elements to displace the same laterally toward each other; a plurality of 50 relatively movable, intercalated, friction plates interposed between said elements; a main spring resistance; and means for restoring said elements and plates to normal position, said last named means including abutments on said elements and certain of said plates co-operating with the spring resistance and abutment means on the remaining plates co-operating with said shoes. 55
13. In a friction shock absorbing mechanism, the combination with a main follower; of a follower-acting friction shell having a transverse end wall and longitudinally disposed, interior friction surfaces diverging laterally toward the axis of the mechanism; a plurality of longitudinally disposed friction elements co-operating with said shell friction surfaces; spreading means co-operating with said elements; a main spring resistance; and a plurality of intercalated, longitudinally disposed friction plates interposed between said elements, said plates being normally spaced from said follower and end wall to provide for preliminary action of the mechanism during the compression stroke. 70
14. In a friction shock absorbing mechanism, the combination with a main follower; of a follower-acting friction shell having interior friction surfaces diverging laterally toward the axis of the mechanism; a plurality of longitudinally disposed friction elements co-operating with said shell friction surfaces, said elements each having a wedge face at one end thereof; a plurality of friction shoes co-operating with said elements; a wedge pressure transmitting means co-operating with said follower and engaging the wedge faces of said elements; a wedge member movable with the shell and co-operating with said shoes; a main spring resistance; and a plurality of longitudinally disposed, relatively movable, intercalated friction plates interposed between said elements. 80
15. In a friction shock absorbing mechanism, the combination with a plurality of sets of intercalated, relatively longitudinally movable friction plates; of a pair of elongated friction elements co-operable with each set of friction plates, said elements being arranged on opposite sides of the corresponding set of plates; a friction member; wedge-acting means at the ends of and co-operating with said elongated friction elements for effecting frictional engagement between said elements and said friction member, said friction member and said each pair of elements having co-operating, longitudinally extending friction surfaces arranged in laterally converging sets, effecting when said elements are acted upon by said means, wedging toward each other of said elements to compress the corresponding set of friction plates; and spring means associated with said wedging means, friction elements and plates for effecting restoration of the parts to normal position upon removal of the actuating force. 100
16. In a friction shock absorbing mechanism, the combination with a plurality of sets of intercalated, relatively longitudinally movable friction plates; of a pair of elongated friction elements co-operating with each set of friction plates and disposed on the opposite sides of the corresponding set of plates; wedging means at the opposite ends of said elongated friction elements effective 110
17. In a friction shock absorbing mechanism, the combination with a main follower; of a follower-acting friction shell having a transverse end wall and longitudinally disposed, interior friction surfaces diverging laterally toward the axis of the mechanism; a plurality of longitudinally disposed friction elements co-operating with said shell friction surfaces; spreading means co-operating with said elements; a main spring resistance; and a plurality of intercalated, longitudinally disposed friction plates interposed between said elements, said plates being normally spaced from said follower and end wall to provide for preliminary action of the mechanism during the compression stroke. 120
18. In a friction shock absorbing mechanism, the combination with a main follower; of a follower-acting friction shell having interior friction surfaces diverging laterally toward the axis of the mechanism; a plurality of longitudinally disposed friction elements co-operating with said shell friction surfaces, said elements each having a wedge face at one end thereof; a plurality of friction shoes co-operating with said elements; a wedge pressure transmitting means co-operating with said follower and engaging the wedge faces of said elements; a wedge member movable with the shell and co-operating with said shoes; a main spring resistance; and a plurality of longitudinally disposed, relatively movable, intercalated friction plates interposed between said elements. 130

to exert pressure on said elements laterally in a plane perpendicular to the line of applied force; means having longitudinally extending friction surfaces co-operating with corresponding frictional surfaces on said elements, said co-operating sets of longitudinally extending friction surfaces being so arranged as to exert a wedging action on each pair of said elements upon the application of a com-

pressing force to said first named wedge means; and a spring means for effecting restoration of the parts to normal position upon removal of the actuating force.

In witness that I claim the foregoing I have hereunto subscribed my name this 10th day of 15 September, 1924.

STACY B. HASELTINE.
